UNITED STATES PATENT OFFICE.

GEORGE C. WILSON, OF FORT WAYNE, INDIANA.

CHIROPRACTIC TABLE.

Application filed January 4, 1921. Serial No. 434,961.

To all whom it may concern:

Be it known that I, GEORGE C. WILSON, a citizen of the United States of America, and resident of Fort Wayne, in the county of 5 Allen and State of Indiana, have invented certain new and useful Improvements in Chiropractic Tables, of which the following is a specification.

This invention relates to improvements in 10 chiropractic tables and the object thereof is to provide apparatus of its class having a yielding central portion in conjunction with adjustable tension means for sustaining the yielding central portion. Another object of 15 the invention is to provide adjustable means for sustaining part of the yielding portion independent of its tension support to limit the extent thereof. And a further object is to so construct the yielding portion of the 20 table that its various parts will be held properly spaced apart throughout its various stages of depression.

The objects of the invention are accomplished by the construction illustrated in 25 the accompanying drawings in which:

Fig. 1 is a plan view of a table embodying the invention, there being parts broken away and in section;

Fig. 2 is a side elevation of Fig. 1, a portion thereof being broken away and in section;

Fig. 3 is a detail view showing an end elevation of adjoining slats, a portion thereof being in section;

Fig. 4 is a detail view showing a section 35 through one of the end slats; and

Fig. 5 is a detail view showing a bottom plan of an end portion of one of the end slats.

Similar characters of reference indicate 40 corresponding parts throughout the several views and referring now to the same:

The frame of the table is comprised of a 45 head pedestal 1 and foot pedestal 2 which are secured in connection with each other by a pair of sills 3 at their lower ends. The pedestal 1 has mounted upon its top a pair of head blocks 4 adapted to be adjustably shifted laterally and serve as a rest for the 50 head of the patient. Within the upper portion of the head pedestal 1 is arranged an equalizing bar 5 having thereon a pair of pulleys 6, and which is secured by means of a series of springs 7 to the front part of the 55 pedestal. Within the upper part of the foot pedestal 2 is arranged a pair of cross-bars 8

and 9 that are coupled together by a series of springs 10. The bar 8 has connection at its respective ends with the corresponding ends of a cable 11 that is trained around the 60 pair of pulleys 6 on the equalizing bar 5 in the head pedestal. The other cross-bar 9 has connections respectively at its ends with a corresponding cable 12 which extends over a pulley 13 mounted in the pedestal and 65 which has connection with a shaft 14 to be wound thereupon. A crank 15 on the outer end of the shaft 14 is provided for turning the shaft, and a ratchet wheel 16 on the shaft and a pawl 17 for engaging it are provided 70 to prevent the shaft from retracting.

The top of the table is formed with a flexible middle portion comprised of a series of slats 18 and 19 through which the cable 11 extends, there being an opening 20 75 in each slat near each end thereof through which the cable passes. The slats are held spaced apart by springs 21 arranged interveningly therebetween on the cable, the ends of the springs extending into corresponding recesses 22 made in the sides of the 80 slats, and the slats are supported yieldingly in position by the cable. The end slats 19 are also pivotally supported at their ends by brackets 23 fixed on the head and foot pedestals respectively which admits of their being tilted more or less as the slats become depressed by the weight of the patient. Also, the slats 19 are provided in their undersides with idlers 24 upon which the cable 90 rides.

Arranged horizontally in the foot pedestal 2, in a plane immediately beneath that of the slats, is a sliding support 25 adapted to be shifted forwardly into position immediately beneath the rearmost slats 18 and 19 and afford support therefor, which has the effect of reducing the extent of flexure of the yielding top of the table. This support may be adjustably moved by any suitable 100 means such as a rack 26 and pinion 27 operated by a hand-wheel 28. An adjustable bolster 29 is also provided for supporting the slats collectively, and includes swinging legs 30 that have pivotal connections at their 105 upper ends with the bolster proper and at their lower ends with the sills 3, there being a notched plate 31 on one of the sills and a latch 32 on one of the legs for retaining the bolster in its supporting position.

In using the invention the patient is positioned on the table in the usual posture,

proper tension being applied to the table 11 by adjustably turning the crank 15 to admit of the desired degree of flexure of the yielding middle portion of the top of the table. The bolster 29 is lowered by swinging it downwardly upon its legs out of the way so as to permit the flexible top to be depressed. When it is desired to confine the flexure of the top more or less to a limited extent the sliding support 25 is moved forwardly so as to sustain one or more of the rearmost slats, thus preventing them from becoming depressed when weight is applied to the yielding top.

15 What I claim is:

1. A chiropractic table having a pedestal at each end and a flexible top portion suspended between the pedestals, the flexible portion being comprised of a series of slats spaced apart and yieldingly supported, there being compression springs arranged interveningly between the slats for holding the same apart.

2. In a chiropractic table, head and foot pedestals; a spring secured equalizing member in the head pedestal; an adjustable tension member in the foot pedestal including means for adjusting same; a cable connected with the equalizing member and having its

ends secured to the tension member; a pivotally supported slat in connection with each pedestal; and a series of slats arranged interveningly between the pivoted slats in supported relation on said cable.

3. In a chiropractic table, a pair of pedestals spaced apart; a flexible top portion suspended between the pedestals and having pivotal connection at each of its ends with the corresponding pedestals; tension means for suspending the flexible top portion between the pedestals; and compression means for spreading the flexible top portion.

4. In a chiropractic table, a pair of pedestals spaced apart; a flexible top portion suspended between the pedestals and having pivotal connection at its ends therewith; tension means for supporting the flexible top portion; and an adjustable bolster adapted to sustain the entire flexible top portion fixedly thereon.

In testimony whereof I affix my signature, in presence of two witnesses.

GEORGE C. WILSON.
